EXPANSIBLE PISTON

Wesley Wilson, Chicago, Ill.

Application August 20, 1934, Serial No. 740,574
Renewed June 5, 1937

7 Claims. (Cl. 309—12)

My invention relates to a piston construction and more specifically to expansible pistons for use in internal combustion engines.

It has been found that pistons of internal combustion engines wear in such a way as to develop "piston slap" due to the side pressure to which the pistons are subjected. Various devices have been proposed with a view to remedying or lessening the bad effects of this wear, including 5 spring expanders and screw expanders. The spring devices, however, are open to the objection that they cause considerable pressure to be exerted by the piston on the cylinder walls, resulting in excessive wear. The screw devices are 10 open to the objection that there is no automatic take-up, so that it is necessary to adjust them from time to time to take up the wear.

One of the objects of my invention is to provide means for exerting pressure to expand the piston, controlled in its pressure-exerting action 20 by wear due to the movement of the piston. This prevents the spring pressure from excessively expanding the piston, thus avoiding the objection to the present spring expanders, and it provides an automatic wear-controlled take-up, thus avoiding 25 the objections to the present screw take-up. This device may be installed in a new motor and provides an automatic take-up for the expansible piston during the life of the motor. With the present types of piston expanders it is necessary 30 to dismantle the motor to install or adjust them.

In the drawing, in which several forms of my invention are shown,—

Figure 1 is a bottom plan view of a piston and associated parts embodying my invention; 35

Fig. 2 is a sectional view substantially on the line 2—2 of Fig. 1;

Fig. 3 is a detail view showing the wrist pin and associated parts;

Fig. 4 is a bottom plan view showing another form of piston and associated parts;

Fig. 5 is a bottom view of another form of piston and associated parts embodying my invention;

Fig. 6 is a bottom view of another form of piston and associated parts; and

Fig. 7 is a bottom view of another form of piston and associated parts.

Referring to the drawing in detail, and first to Figs. 1, 2, and 3, the construction shown therein 50 comprises an expansible piston 1, which may be of aluminum or other suitable material, a connecting rod 2, and a hollow wrist pin 3 to which the upper end of the connecting rod is clamped by means of a screw 4. The wrist pin is mounted

for a slight rocking movement in suitable bearing bosses 5 on the piston 1.

I take advantage of the wear occasioned by the slight rocking movement of the wrist pin to control the expanding action of the spring-pressed wedge 6 which engages the inclined surfaces 7 adjacent the split 8 in the piston and which tends to expand the piston. This wedge 6 may be in the form of a yoke having openings in its side portions 9 through which the rockable wrist pin extends. Suitable helical compression springs 10 are provided surrounding the pins 11 formed on the sides of the yoke for exerting pressure to expand the piston. These springs can force the wedge no further than the 15 wrist pin will permit, as the edges of the openings in the yoke engage the wrist pin, thus restraining its wedging action. However, the spring pressure on the yoke will cause a wearing action on the edges of the openings in the yoke 20 so that as the wrist pin rocks, the edges of the openings in the yoke will wear and permit the wedge to move very gradually in a direction to expand the piston. The wearing action may be controlled, either by cutting away a portion of 25 the edge of the opening on the side toward the spring, as shown at 12 in Fig. 2, or by providing the edge of the opening on the side toward the spring with material having the desired wearing qualities, which will cause just the proper gradual movement of the wedge, as shown at 13 in Fig. 3. 30

With this construction, it will be seen that the full pressure of the spring is prevented from being exerted as a force tending to expand the cylinder but that the gradual wearing action due 35 to the rocking of the wrist pin will allow a very gradual movement of the wedge which will take up the wear on the piston at a rate proportional to the extent of use of the piston. It will also be seen that there is a compensating action between the wear of the piston itself and the wear on the edge of the opening in the wedge due to the wrist pin action, since if the piston wears comparatively rapidly—say, due to poor lubrication—the poor lubrication will at the same time 40 produce increased wear on the expander bearing, thus permitting a comparatively greater rate of expansion than would result with normal lubrication. 45

The construction of Fig. 4 is quite similar 50 to that just described, except that the expanding action of the piston is effected by a resilient curved plate 14 engaging opposite sides of the split 8 in the piston and that the springs 11 which act on the yoke are backed up by an- 55

other yoke 15 mounted on the bearing bosses 5 of the piston.

The construction of Fig. 5 is similar to those previously described except that here the springs 11 which exert pressure on the yoke 16 are backed up by the bearing bosses on the piston itself and the further distinction that the bearing bosses are split, as indicated at 17, thus providing a construction in which the smaller of the split portions 18 may yield under the wearing action of the rocking movement of the wrist pin and the spring pressure exerted on the yoke. This construction will also act to take up for wear in the wrist pin bearing itself.

In Fig. 6 is shown a construction in which the piston is split at diametrically opposed points and two expanding members 19 are substituted for the expanding yoke of the previous constructions. In this form two spring-pressed pressure-exerting members are provided, each pivotally mounted on the piston as indicated at 20, adjacent a split in the piston, each having a portion through which the wrist pin extends, and each provided with a spring 11 for exerting an expanding action on the pressure-exerting member. Each of these pressure-exerting members is provided with an extension 21 for engagement with a lug 22 on the edge of the split in the piston. This lug acts as a guide for preventing radial movement.

The construction of Fig. 7 is similar to that of Figure 1 except that in this form the wear takes place on a bushing 23 of suitable material secured to the wrist pin to rock therewith. In this form, the wear on the bushing permits the slow graduated movement of the expanding wedge 6 under the action of the springs 11. In this form the yoke is shown as made in two parts spaced from each other as indicated at 23^a and 40 having provisions for adjustably spacing the parts of the yoke. The means shown for this purpose comprise a screw 23^b having an enlarged portion 23^c threaded into one side of the yoke and having a reduced portion 23^d swivelled in the 45 other side of the yoke. With this construction the yoke members may be adjusted to the desired spaced position and may be held in this position by means of a lock nut 23^e. This adjustment may be specially useful when the 50 pander is being applied to a worn piston as it enables the repairman to adjust the yoke to secure proper relation between the piston and cylinder.

Having thus described the invention, what is 55 claimed as new and is desired to secure by Letters Patent is:

1. A piston construction comprising an expandable cylindrical piston for operating in a cylinder, a wrist pin rockably mounted with respect to said piston, means exerting force to expand said piston, and wearable means controlled in its action by wear accompanying the rocking movement of said wrist pin preventing the force of said force-exerting means from being exerted to such a distance as to press the piston against the cylinder wall but enabling a slow restrained movement of said force-exerting means as the wear progresses.

2. A piston construction comprising an expandable cylindrical piston for operating in a cylinder, a wrist pin rockably mounted with respect to said piston, spring means exerting force to expand said piston, and wearable means controlled in its action by wear accompanying the 75 rocking movement of said wrist pin preventing

the force of said force-exerting means from being exerted to such a distance as to press the piston against the cylinder wall but enabling a slow restrained movement of said force-exerting means as the wear progresses.

3. A piston construction comprising an expandable cylindrical piston for operating in a cylinder, a wrist pin rockably mounted with respect to said piston, spring means exerting force to expand said piston, and wearable means controlled in its action by wear accompanying the rocking movement of said wrist pin preventing the force of said force-exerting means from being exerted to such a distance as to press the piston against the cylinder wall but enabling a slow restrained movement of said force-exerting means as the wear progresses, said force-exerting and wearable means comprising a force-transmitting member having an opening through which said wrist pin extends, said spring means exerting force on said force-transmitting member to cause wear on the edges of said opening due to the rocking movement of the wrist pin.

4. A piston construction comprising an expandable cylindrical piston for operating in a cylinder, a wrist pin rockably mounted with respect to said piston, a connecting rod secured to said wrist pin, spring means exerting force to expand said piston, and wearable means controlled in its action by wear accompanying the rocking movement of said wrist pin preventing the force of said force-exerting means from being exerted to such a distance as to press the piston against the cylinder wall but enabling a slow restrained movement of said force-exerting means as the wear progresses, said force-exerting and wearable means comprising a pair of force-transmitting members straddling said connecting rod and having openings through which said wrist pin extends, said spring means exerting force on said force-transmitting members to cause wear on the edges of said openings due to the rocking movement of said wrist pin.

5. The combination of a piston having an expandable skirt, a member mounted in said skirt and being free to oscillate therein, an expander element having a portion thereof in wear-engaging relationship with said member and having another portion engaging said expandable skirt, and resilient means engaging said expander element to urge the same into engagement with said skirt as said expander element wears in use.

6. In a piston having an expandable skirt, means mounted therein in free oscillating relationship thereto, other means contacting said expandable skirt and arranged in wear-engaging relationship with said first-mentioned means, and resilient means engaging said second-mentioned means and tending to preserve said contacting relationship as said second-mentioned means wears in use.

7. An expanding piston construction comprising a piston having an expandable skirt, a member carried by said piston mounted for relative movement with respect thereto, expansion-controlling means in wear-engaging relationship with respect to said movable member and in expansion-controlling relationship with respect to said expandable skirt, said expanding piston construction having means for urging said expansion-controlling means into wear-engaging relationship with said movable member and into expanding relationship with respect to said expandable skirt.
